(57) **CLAIM**

The ornamental design for a buckle assembly as shown and described.

DESCRIPTION

FIG. 1 is a top front left side perspective view of a buckle assembly, showing our new design;

FIG. 2 is a top plan view thereof;

FIG. 3 is a bottom plan view thereof;

FIG. 4 is a right side view thereof;

FIG. 5 is a left side view thereof;

FIG. 6 is a rear view thereof;

FIG. 7 is a front view thereof;

FIG. 8 is a top front left side perspective view of a first component of the buckle assembly, shown in isolation for clarity of illustration;

FIG. 9 is a top plan view thereof;

FIG. 10 is a bottom plan view thereof;

FIG. 11 is a right side view thereof;

FIG. 12 is a left side view thereof;

FIG. 13 is a rear view thereof;

FIG. 14 is a front view thereof;

FIG. 15 is a top front left side perspective view of a second component of the buckle assembly, shown in isolation for clarity of illustration;

FIG. 16 is a top plan view thereof;

FIG. 17 is a bottom plan view thereof;

FIG. 18 is a right side view thereof;

FIG. 19 is a left side view thereof;

FIG. 20 is a rear view thereof; and,

FIG. 21 is a front view thereof.

Broken lines depict portions of the buckle assembly which form no part of the claimed design.

1 Claim, 21 Drawing Sheets
